DESIGN FOR A COMBINED DISPLAY AND VENDING STAND FOR NEWSPAPERS, PERIODICALS, AND THE LIKE

James Leslie Wright, Hamilton, Ontario, Canada

Application May 17, 1934, Serial No. 51,815
In Canada April 10, 1934

Term of patent 3½ years

To all whom it may concern:

Be it known that I, JAMES LESLIE WRIGHT, a subject of the King of Great Britain, residing at Hamilton, in the county of Wentworth, Province of Ontario, Dominion of Canada, have invented a new, original, and ornamental Design for a Combined Display and Vending Stand for Newspapers, Periodicals, and the like, of which the following is a specification, reference being had to the accompanying drawing, forming part thereof.

The figure is a perspective view of a combined display and vending stand for newspapers, periodicals, and the like, showing my new design.

I claim:

The ornamental design for a combined display and vending stand for newspapers, periodicals, and the like, as shown.

JAMES LESLIE WRIGHT.
